UNITED STATES PATENT OFFICE.

CHARLES F. WINDER, OF HOLLYWOOD, CALIFORNIA, ASSIGNOR TO THE SYMPHONAEER CO., A CORPORATION OF DELAWARE.

ORGAN.

Application filed November 30, 1925. Serial No. 72,212.

This invention relates to organs, and in particular to a novel means for controlling the swells. At the present time in organ construction it is customary to provide what is termed a swell pedal, which is controlled by the foot. It is also customary to provide, and in fact, standard practice to provide, foot pedal keys, and it is practically impossible to operate the foot control for a swell when both feet are required on the foot pedal keys, with the result that no expression is given whatsoever. If we consider such musical compositions as the Bach Fugue, the difficulty of playing such a composition with a present organ will immediately be apparent. There is thus developed what I am pleased to term "a one-legged organist"; in other words, that type of organist who keeps one foot on the swell pedal and uses the other foot in an attempt to play the foot pedal keys. Where truly fine organ playing is required this so-called one-foot pedal work and key work is extremely poor technique.

An object of my invention is to overcome the difficulties heretofore present in the control of the swell or expression shutters of an organ and to provide an organ with means whereby both feet may be used for playing the foot pedals with the hands controlling the expression or swell, in accordance with pressure exerted on the keys of the manual keyboard. The advantage of this is immediately apparent, and compositions that heretofore have been difficult of execution are easily played by the expert organist. At best, gymnastic foot-work has been overcome. My invention goes a step further, in that I utilize body movement in controlling the swell and expression so that after a key or keys on the manual keyboard have been depressed a certain distance to produce a certain expression, this expression or swell can be maintained by the organist by shifting his body position. I accomplish this latter result in any one of several manners, such as by providing a rocker-like motion to the seat or bench, the degree of movement of such seat or bench controlling the expression shutters. For that matter, the back of the seat or bench could be movable, so that by pressing backwardly against such back the expression shutters could be maintained in any desired position.

The invention has for further objects the provision of a novel means for controlling

the expression or swell shutters of an organ which is inexpensive of manufacture, simple in construction and generally superior in point of relative simplicity and durability.

With the above and other objects in view, the invention consists in the novel and useful provision, formation, construction, association and relative arrangement of parts, members and features, all as shown in certain embodiments in the accompanying drawings, described generally and more particularly pointed out in claims.

In the drawings:

Figure 1 is a fragmentary side elevation of two manual key-boards both of which incorporate the invention;

Figure 2 is a fragmentary and partially sectional plan view of features of the organ operated by the manuals shown in Figure 1;

Figure 3 is a cross sectional view of the pressure box such as used in organ practice;

Figure 4 is a plan view of pedal keys such as are now in general use, and showing a further portion of the invention for controlling the expression or swell;

Figure 5 is a side elevation of the console with one form of seat or bench which may control the expression or swell shutters;

Figure 6 is a diagrammatic view of certain elements of the invention adapted to be associated with the seat or bench for controlling the expression or swell shutters; and,

Figure 7 is a fragmentary vertical sectional view of certain motors used in practicing the invention.

Corresponding parts in all the figures are designated by the same reference characters.

The complete invention involves the keyboard and means associated therewith for actuating the swell shutters and the said means are separately shown in Figures 1 and 2. The invention as an entirety for the two figures is designated by A, of which B represents the manual keyboard having two manuals *a* and *b*, and the shutter mechanism is designated as an entirety by C, which mechanism includes shutters *c* and motors *d* for actuating the shutters.

At the present time almost universally a series of shutters following the Venetian blind principle are placed in front of or act as the front portion of an organ chest. These shutters are actuated by a lever so that they open or close simultaneously a predetermined amount. Within the organ

chamber is the chest, said chest having pipes of various sizes, shapes and diameters, to produce the tones desired.

In the present invention the shutter mechanism C is standard of arrangement with the exception of the expression shutters c which are of the form shown and claimed in my application for patent executed this 25th day of November, 1925. As illustrating the invention I have shown two organ chambers e and f within which chambers are chests g and h. The chests contain the pipes. The expression shutters c close or open the front portion of the said chambers, so that the music emitted by the pipes may be heard in a room adjacent the organ chambers. I might say that this is not always true, but depends upon the effect desired, such as for echoes and the like, and the chest might be removed some distance from the normal organ room. The motors d comprise a series of small bellows j and the number of such motors used will depend upon the degree of expression desired, and to this end the motors will be directly controlled by certain mechanism of the invention associated with the manual keyboard. Two of the motors are shown in cross section in Fig. 7 and the type of motor therein depicted is of standard practice such as is universally used at the present time by organ manufacturers. In detail, I will say that each motor includes a disc 1 with a flexible element or bellows 2 joining opposed faces of adjacent discs of two of such motors. A port 3 extends through the disc 1 and opens between the adjacent faces of two of such discs and within the bellows portion and with a suitable tube or tubes 4 communicating with the port 3 so that air may be forced through said port to expand the bellows. The tubes are flexible and communicate with a pressure box k. It will be noted that there is a partition or leg 5, against the surface of which, a motor as shown at 6 abuts, and the last motor shown at 7 is directly associated with a rod 8 which is movable to control the opening or closing of the shutters c. As between the motors shown at 6 and 7 I have numerous other motors the number of which will depend upon the degree of expression or opening of the expression shutters desired, as before pointed out. Thus if air is emitted between the motor 6 and the next motor adjacent thereto, the rod 8 will be moved a certain distance inwardly of the organ chamber. In the showing of Fig. 2 the said rod 8 has been moved by five of said motors and the shutters are partially opened. The pressure box which controls operation of the motors is shown in enlarged cross section in Fig. 3, and this pressure box is of standard practice. However, 9 is a casing, the bottom wall 10 of which is formed to carry mechanism m for controlling operation of

the motors, which is to say, permitting air to expand the bellows or to exhaust the bellows thereof.

Figure 3 illustrates one of such mechanisms m for controlling the bellows between two adjacent motors. The pressure box base 10 is bored at 11 so as to confine a magnet 12, the pole pieces of which are received and carried by a part 13 associated with the base 10. The part 13 is formed with a port 14 in communication with the opening or bore 11 and such part 13 is chambered as shown at 15 with the said port 14 communicating with such chamber. Immediately below the port 14 and of enlarged diameter is a second port 16 and normally closing this port is a pallet or keeper 17 maintained in position over such port by guides 18. The ends of the poles of the magnets are immediately above the top surface of the pallet or keepers 17. The base 10 is formed with a bore or port 19 communicating with the chamber 15 and a member 20 formed with a port 21 is in communication with the port 19 and likewise in communication with the interior of a motor 22. This motor constitutes a small bellows having a bellows part 33 of flexible material interposed between a fixed and a movable disc 24 and 25 respectively. The base 10 is chambered at 26 and has an opening of reduced diameter 27 communicating with the chamber and with the interior of the pressure box and which opening is normally closed by a disc 28. Immediately below the base 10 and closing the chamber 26 is a piece 29 formed with a port or opening 30 in communication with the chamber 26. Carried by the disc 25 and extending through the chamber 26 and outwardly thereof is a stem 31. The stem carries discs 28 and 33, which discs are spaced and adjustably locked on said stem by nuts 32 and 34 respectively. A port 35 is in communication with the chamber 26, and it will be noted that one of the tubes 4 communicates with such port 35.

As a brief statement of the operation of this device just described, will say the pressure box is normally air-tight and has air forced within the same by a suitable compressor.

In Figure 5 I have shown in dotted lines at 36 the balance or expression pedal which is associated with the console, and when this balance or expression pedal is moved by the foot the shutters are opened or closed, the degree of opening of the shutters depending upon the movement of the balance pedal. It is to be understood that this is standard practice. When the balance pedal 36 in organs, as now installed, is moved, and assuming the parts in the position of Fig. 3, the magnet 12 is energized, and the pedal or keeper 17 is drawn upwardly by the pole pieces of the magnet which will close the

port 14 and allow the air in the bellows of the motor 22 to escape through the port 21 into the chamber 15 and outwardly to the atmosphere through the port 16. This will occur for the reason that the air pressure within the pressure box will move the bottom disc 25 of such motor upwardly, and in doing so the disc 28 which closes communication to the port 27 will be lifted and air from the pressure box will enter the chamber 26 and pass through the port 35 and the tube 4 to one of the motors *d*. The air cannot escape from the pressure box to the atmosphere from the chamber 26, for the reason that the disc 33 will close the port 30. When the pressure is relieved from the balance or expression pedal 36 and it returns to normal, the pallet 17 will drop to the position shown in Fig. 3 and air in the pressure box will then pass through the port 14 into the chamber 15, through the ports 19 and 21, and expand the bellows of the motor 22, forcing the disc 28 to close entrance to the port 27 at the same time moving the disc 33 from the member 29 where it formerly closed the port 30, with the result that the air in the motor *d* will be exhausted to the atmosphere through the tube 4, the port 35 and the port 30.

This action is very rapid. As has been stated, there will be as many of the devices shown in Fig. 3 as there are motors *d*.

The difficulties as enumerated in the playing of an organ will now be apparent, for the reason that the feet are required to play upon certain foot keys *n* shown in Fig. 4. 37 and 38 represent the natural and sharp keys respectively which must be played by the feet and the difficulty of properly playing upon such keys and at the same time operating the balance pedal 36 will be apparent. The balance pedal controls the pianissimo, piano, mezzo, forte and fortissimo, and if a composition such as the Bach Fugue is to be played proper pedaling in playing of the keys 37 and 38 is an impossibility, becoming a gymnastic feat on the part of the organist. Due to the difficulty of properly playing the keys *n* and still operating the balance pedal, organists in numerous cases have abandoned technique and keep one foot upon the balance pedal at all times while any key that the other foot happens to strike on the keys *n* is the proper key so far as they are concerned. Music produced by this method of playing an organ is heard in theatres a great deal.

My invention permits proper expression at all times under the direct control of the organist and at the same time leaves both feet free to properly play the keys *n*.

Referring to Fig. 1 and the means B, I have shown two manuals *a* and *b*, and it is of course to be understood that other manuals could be added as desired. The manual

b is constructed in the same manner as the manual *a*, and for this reason only one of the manuals will be described, the same reference characters applying to both of said manuals. The manual *a* includes the usual key 50 which in this case is the natural key, the said key being transversely bored at 51 and 52 to receive pivot pins 53 and 54, which pivot pins are secured to a portion of the key frame 55. The key frame is usually a rectangular member having end pieces 56 and side pieces 57 and 58 joined to such end pieces. The side pieces extend the length of the keys of each complete manual and beneath the said keys, and the rear side piece 58 acts to support the keys of one manual. The front piece 57 of the frame is provided with guide pins 59 of which there may be one or more adapted to be received within bores in the key. The key frame and keys are supported upon a key bed 60 and the key bed has end members 61 and front and rear side members 62 and 63 respectively, thus forming a rectangular frame. Adapted to be associated with the key bed are springs 64 which act to hold the key frame in a position normally raised above the key bed. The front member 62 of the key bed is transversely bored at 65 and a link 66 is passed through such opening and pivotally connected at 67 to the key frame 55. The lower end of such link is pivoted at 68 to a lever 69 which is in turn pivotally carried by a bracket 70, the bracket being associated with the key bed 60. Thus, if the key shown at 50 were depressed sufficiently the same would contact with the key frame and move the key frame downwardly, such downward movement being resisted by the spring or springs 64, and such downward movement would move the link 66 and in turn move the lever 69, the end 71 of which lever would be raised. The said lever adjacent the end 71 carries a knife edge 72 and this knife edge is adapted to contact in step sequence with contacts 73. Thus, if the lever was depressed slightly it might contact with the first contact 73 and a complete depression of the lever would cause the knife edge to contact with all of the said members 73. There are as many contacts and wires leading from said contacts to the pressure box *k* as there are magnets 12 adapted to actuate motors *j*. Thus, for any manual the swell or expression is directly under the control of the operator of said manual by a mere depression of the key or keys in said manual. By holding the finger on one of the keys of the manual and continuing to depress the same the swell is increased by completely opening all of the shutters *c*. Each manual has its key frame and when the key frame is depressed by any one key of the manual the swell or expression is controlled. For the first time, so far as the in-

ventor is aware, the swell or expression is directly under control of the organist by a mere fingering of the keys, and the feet are left free to properly play the pedal keys.

5 In Figure 1 one of the keys of the manual *b* has been depressed and the knife edge 72 has engaged five of the contacts 73 and the leads from said contacts have operated five of the motors *j* in a manner heretofore described to partially open the expression shutters *c*. When the finger leaves the key to release the key frame the spring shown at 80 and which is interposed between a wall chamber *e* and a carrier on the rod 8, will move the rod 8 so as to close the shutters *c*. The system that I have just described permits ordinary fingering of the keys of the different manuals without operating the key frame, and it is only when expression is desired that the keys are further depressed to move the key frame. A second method of controlling the expression shutters is shown in Figs. 4, 5 and 6, wherein the seat or bench *p* normally placed in front of the console *q* 25 is adapted to actuate a switch to control the opening or closing of the expression shutters. In this instance, the side supports 100 have one portion thereof curved, as shown at 101, and one of the side supports carries a bracket 102 adapted to engage an arm 103 when the seat or bench is tipped forwardly, and which arm 103 is bell-cranked as shown at 104 so that the same will be revolved when the bracket 102 engages the same to 30 move a contact arm 105 which carries a knife edge 106 adapted to engage in sequence the series of contacts 107 in all respects the same as does the contact 73 and with electrical connections 108 leading from said contacts to the motor *d*. If desired, the back of the seat or bench, if one were placed thereon, might be utilized to actuate a switch to control movement of the motors *d*. The seat or bench *p* may be maintained 35 in a definite position of placement in front of an organ by means of a spring 109 entering within a curved portion 110 of the seat support or supports. This tipping of the seat or bench or movement of the back also directly controls the opening of the shutters after the key frame of the different manuals has been actuated and to this end the said seat or bench by its tipping may act in direct conjunction with such manuals. For

instance, if great expression is necessary 55 and at the same time rapid fingering tipping of the seat forward or movement of the back of the seat could control the expression while ordinary fingering might be resorted to on the different keys of the manuals.

60 It is of course to be realized that the method shown in the drawings and described for the seat is not the only one that could be incorporated, and within the interpretation of my invention I might pivot the seat.

65 It is also within the scope of my invention to provide separate switches to be operated from or controlled from the seat either singly or collectively and whereby the expression can be controlled.

70 It is obvious that various changes and modifications may be made in practicing the invention, in departure from the particular showing of the drawings, without departing from the true spirit of the invention.

75 Having thus disclosed my invention, I claim and desire to secure by Letters Patent:

1. Means for controlling the swell of an 80 organ, said organ including the usual console and a seat for the organist; means associated with the seat whereby upon movement of a portion of said seat the expression of the organ may be controlled.

2. Improvements in organs having the 85 usual organ chamber and shutters for opening or closing a portion of said chamber to vary the expression of the organ, a console and a seat for the organist in front of said console; movement of a portion of the seat 90 by the organist controlling the opening or closing of the shutters.

3. Improvements in organs having a console and a seat for the organist adjacent said console, and an organ chamber the expression of which is controlled by expression shutters, there being means controlled by the tipping of the seat to control opening or closing of the shutters; said means including a switch, and a motor coupled with the 100 shutters, variable movement of the switch providing variable movement of the motor to provide variable movement of the shutters.

105 In testimony whereof, I have signed my name to this specification.

CHARLES F. WINDER.
